US0D1059702S

(12) **United States Design Patent** (10) **Patent No.:** **US D1,059,702 S**
(45) **Date of Patent:** **** Jan. 28, 2025**

(54) **AUTOMATED DISINFECTION DEVICE**

(71) Applicants: **Wai Hong Ho**, Hong Kong (CN);
Johnson Yiu-Nam Lau, Hong Kong (CN)

(72) Inventors: **Wai Hong Ho**, Hong Kong (CN);
Johnson Yiu-Nam Lau, Hong Kong (CN)

(73) Assignee: **AVALON STERITECH LIMITED**,
Hong Kong (CN)

(**) Term: **15 Years**

(21) Appl. No.: **29/820,458**

(22) Filed: **Dec. 22, 2021**

(51) LOC (15) Cl. **15-05**

(52) U.S. Cl.

USPC **D32/15**

(58) **Field of Classification Search**

(57) **CLAIM**

The ornamental design for an automated disinfection device as shown and described.

DESCRIPTION

FIG. 1 is a first perspective view of an automated disinfection device;

FIG. 2 is a second perspective view thereof;

FIG. 3 is a back view thereof;

FIG. 4 is a bottom view thereof;

FIG. 5 is a front view thereof;

FIG. 6 is a left view thereof;

FIG. 7 is a right view thereof; and,

FIG. 8 is a top view thereof.

The broken lines in the drawings depict portions of the automated disinfection device that form no part of the claimed design.

1 Claim, 8 Drawing Sheets
